The ornamental design for a light emitting diode, as shown and described.

DESCRIPTION

This application is related to U.S. Design application Ser. Nos. 29/336,754, 29/336,787 and 29/336,790, all filed May 8, 2009 and titled Light Emitting Diode.

FIG. 1 is a front perspective view of a light emitting diode showing the claimed design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
